UNITED STATES PATENT OFFICE.

HENRY H. LOGAN, OF CHICAGO, ILLINOIS.

SAFETY CONTROL DEVICE.

Application filed August 2, 1923. Serial No. 655,322.

To all whom it may concern:

Be it known that HENRY H. LOGAN, a citizen of Great Britain, who has declared his intention of becoming a citizen of the United States, and a resident of Chicago, in the county of Cook and State of Illinois, has invented a new and useful Improvement in Safety Control Devices, of which the following is a full, clear, and exact description.

10 My invention relates to improvements in safety control devices, and it consists in the combinations, constructions, and arrangements herein described and claimed.

This application is a continuation in part 15 of my application for safety control device, Serial No. 517,602, filed November 25, 1921, and allowed July 7, 1923, which has matured into Patent No. 1,480,170, January 8, 1924. This application shows a safety control device 20 which comprises a brake that is adapted to be automatically applied to a hoisting mechanism when the car reaches a predetermined point in its ascent and descent; and novel means for applying the brake instantaneously or gradually so as to bring the car to an abrupt stop or to a slow stop. The novel means for actuating the brake quickly or slowly was claimed in my co-pending application. The present application is especially directed to the releasing mechanism for the brake.

An object of my invention is to provide a braking mechanism which is electrically operated, the releasing mechanism being 35 constructed so as to hold a relatively great weight with but little force being required to hold the weight in its uppermost position.

A further object of my invention is to provide a device of the character described 40 which is adapted to instantly release the weight as soon as the current has been shut off.

A further object of my invention is to provide a device of the character described 45 in which the control mechanism and the braking mechanism are mounted on a single base.

A further object of my invention is to provide a device of the character described 50 which is simple in construction and which may be readily connected to a hoisting mechanism with but slight alterations being necessary in the latter.

Other objects and advantages will appear in the following specification, and the

novel features of the invention will be particularly pointed out in the appended claims.

My invention is illustrated in the accompanying drawings, forming part of this application, in which—

Figure 1 is a side elevation of the device, Figure 2 is a front elevation of the upper portion of the device, and

Figure 3 is a vertical section through the oil cylinder control.

In carrying out my invention, I provide a base 1 which carries a shaft 2, the shaft being connected to the braking mechanism of a hoist (not shown), whereby a partial rotation of the shaft will apply the brakes to the hoisting mechanism. An arm 3 is rigidly secured to the shaft 2 and carries a weight 4 at its free end. The weight 4 is adapted to drop from the full line position to the dotted line position when the arm 3 is released by a mechanism hereinafter described. The movement of the weight 4 into its lowermost position applies the brake to the hoisting mechanism.

The means for causing the weight 4 to move downwardly rapidly or slowly has been clearly described and claimed in my co-pending application, Serial No. 517,602, and therefore needs but a general description in the present application. This mechanism comprises an oil cylinder 5 that is pivotally mounted to the base 1 at 6, and which carries a piston rod 7 that is connected to the arm 3. A valve, indicated generally at 8, when closed is adapted to permit the arm 3 and weight 4 to move downwardly slowly, and when open, to permit a rapid descent.

A cam 9 is mounted upon the base 1 and is adapted to turn through an approximate complete revolution during the entire movement of the car that is actuated by the hoisting mechanism. Lugs 10 and 11 are secured to the cam 9 and are adapted to contact with a cam follower arm 12 so as to swing the arm downwardly. The arm 12 is operatively connected to the valve 8 by means of an arm 13, a rod 14, a lever 15, and a link 16. When the arm 12 is actuated by either of the lugs 10 or 11, the valve 8 is opened so as to permit a quick drop of the weight 4. This quickly applies the brake to the hoisting mechanism and brings the car to an abrupt stop. At the time the arm 12 is

moved by either of the lugs 10 or 11, the current to the hoist actuating mechanism is cut off, whereby the weight 4 is released.

Means for holding the weight in raised position and for instantly releasing the weight when the current is cut off, is clearly shown in Figure 1. A lever 17 is pivotally secured at 18 to a frame 19, that in turn is carried by the base 1. The lever 17 has a recess 20 therein which is adapted to receive a hook 21 which is carried by the arm 3. The lever 17 when in closed position is disposed in such a position that it can withstand a relatively great pulling force without being rotated about the pin 18. With this construction a very small retaining force can be used for supporting a relatively great weight. The lever 17 is connected to an arm 22 by means of a link 23. Here again it will be noted that the link 23 and arm 22 are disposed substantially at right angles to the lever 17 so that the arm 22 can withstand great pull upon the link 23 without requiring much force to hold the arm 22 in closed position. A small magnet 24 is employed for holding the arm 22 in closed position. This magnet 24 is preferably connected in either of two ways, i. e., first in series with the oil switch (not shown), or with a circuit breaker (not shown), or by a switch operated by the governor X on the controller, whereby an overload, a failure of the current, or the opening of the circuit breaker or governor operated switch will de-energize the magnet; and second, in series with a switch (not shown) which is operated by the cam 9. The magnet is also in series with a plurality of switch boxes (not shown) which are disposed along the line of travel of the cage, one of the switches being disposed in the cage itself so as to be readily actuated by the person within the cage. When the current to the magnet 24 is cut off by any one of the foregoing ways, the weight 4 will cause the arm 22 to swing into the dotted line position, whereupon the weight will be released from the recess 20. The piston 7 will now regulate the speed of the weight 4 in its downward movement. From the foregoing description of the various parts of the device, the operation thereof may be readily understood. When the weight 4 is released before the cage is at the end of its movement either in an upward or downward direction, the valve 8 will be closed so as to cause the weight 4 to move downwardly slowly and to gradually apply the brakes. The closing of the valve 8 at this time is due to the disengagement of the cams 10 and 11 with the cam arm 12 which is connected to the valve through the connecting rod and levers 14, 15, and 16, respectively. When the cage is near its uppermost or lowermost position, the weight 4 when released will quickly apply the brakes

so as to bring the car or cage to an abrupt stop. This is due to the fact that the valve 8 is open since one of the cams 10 and 11 is in engagement with the cam arm 12 connected with the valve 8. The recess 20 is curved so as to force the hook 21 out of the recess as the weight 4 pulls the lever 17 into the dotted line position.

Since the brake actuating mechanism and the releasing mechanism are mounted upon a single base, the device may be readily connected to the hoisting mechanism in a minimum length of time. The weight 4 carries a switch member 25 that is adapted to contact with the switch member 26 when the weight is in its uppermost position. This master control switch is open when the weight 4 drops into its lowermost position. The device may be readily reset after once being actuated. This is accomplished by merely swinging the weight 4 from the dotted line position into the full line position, the hook 21 engaging with the lever 17 during this movement so as to swing the lever into its closed position. The magnet 24 is now adapted to hold the arm 22 in closed position.

The device is very simple in construction and provides a novel means for automatically controlling the cage. The device is adapted to automatically stop the movement of the cage in case the engineer who is controlling the device is careless or through accident is unable to operate the control mechanism. The device is also adapted to stop the cage in case an accident happens to the actuating mechanism or in case the cage is not retarded soon enough at the end of its movement. The device is combined into a single unit and can therefore be readily moved when desired.

The piston rod has a piston 27 mounted thereon, the piston having a plurality of large openings 28 therein. A spring pressed disc 29 closes the openings when said piston is moving downwardly. The piston is also provided with a small opening 30 through which the oil flows when the hoist 4 is released. A by-pass 31, controlled by the valve 8, permits the oil to quickly flow from beneath the piston to above the piston when the valve is open. The cylinder is also provided with a groove 32 adjacent to the top thereof, this groove allowing the oil to quickly flow to the top of the piston when the piston starts on its downward movement.

I claim:

1. A device of the type described comprising a support, a shaft carried by said support, a weighted arm rigidly secured to said shaft, a magnet, a plate pivotally carried by said support and adapted to contact with said magnet and to be held against movement when said magnet is energized, a second arm pivotally carried by said sup-

- port, a link connecting said plate with said second named arm, said second named arm having a recess therein, and a hook carried by said weighted arm and adapted to be received in the recess of said arm.
2. A device of the type described comprising a support, a shaft rotatably mounted in said support, a weighted arm rigidly secured to said shaft, a second arm pivotally carried by said support, a magnet adapted to lock said second named arm against movement when said magnet is energized, said second named arm having a recess therein, a hook carried by said weighted arm and adapted to be received in the recess of said second named arm, and means for controlling the movement of said weighted arm when said weighted arm is released by said second named arm.
3. A device of the type described comprising a support, a shaft rotatably mounted in said support, a weighted gravity actuated arm rigidly secured to said shaft, and an electrically controlled locking means for normally preventing the movement of said arm except when released by said locking means.
4. A device of the type described comprising a support, a shaft rotatably mounted in said support, a weighted gravity actuated arm rigidly secured to said shaft, and an electrically controlled locking means for normally preventing the movement of said arm except when released by said locking means, said controlling means being adapted to permit said weighted arm to swing rapidly or slowly.
5. A device of the type described comprising a support, a shaft rotatably mounted in said support, a weighted arm rigidly secured to said shaft, a second arm pivotally carried by said support, a magnet adapted to lock said second named arm against movement when said magnet is energized, said second named arm having a recess therein, a hook carried by said weighted arm and adapted to be received in the recess of said second named arm, and means for controlling the movement of said weighted arm when said weighted arm is released by said second named arm, said controlling means being adapted to permit said weighted arm to swing rapidly or slowly.
6. A device of the type described comprising a support, a shaft rotatably mounted in said support, a weighted gravity actuated arm rigidly secured to said shaft, an electrically controlled locking means for normally preventing the movement of said arm, a cylinder pivotally carried by said support, said cylinder having a fluid therein, and a piston disposed in said cylinder and operatively connected to said arm, said piston having a small opening therein for the passage of the fluid therethrough, whereby said piston will slowly move downwardly in said cylinder when said arm is released by said locking means.
7. A device of the type described comprising a support, a shaft rotatably mounted in said support, a weighted gravity actuated arm rigidly secured to said shaft, an electrically controlled locking means for normally preventing the movement of said arm, a cylinder pivotally carried by said support, said cylinder having a fluid therein, and a piston disposed in said cylinder and operatively connected to said arm, said piston having a small opening therein for the passage of the fluid therethrough, whereby said piston will slowly move downwardly in said cylinder when said arm is released by said locking means, and means for permitting the piston to move rapidly downward in said cylinder.
8. A device of the type described comprising a support, a shaft rotatably mounted in said support, a weighted gravity actuated arm rigidly secured to said shaft, an electrically controlled locking means for normally preventing the movement of said arm, a cylinder pivotally carried by said support, said cylinder having a fluid therein, a piston disposed in said cylinder and operatively connected to said arm, said piston having a small opening therein for the passage of the fluid therethrough, whereby said piston will slowly move downwardly in said cylinder when said arm is released by said locking means, a bore in the wall of said cylinder and communicating with the top and bottom of said cylinder, and an automatically controlled valve disposed in the bore.
9. In a device of the type described, a support, a magnet carried by said support, a plate pivotally carried by said support and adapted to abut said magnet and to be prevented from movement when said magnet is energized, an arm pivotally carried by said support, said arm having a recess therein, a link connecting said arm with said plate, a movable member, and a hook carried by said movable member and adapted to be received in the recess of said arm.
10. A device of the type described comprising a support, a weighted gravity actuated arm pivotally carried by said support, an electrically controlled locking means adapted to normally prevent said arm from movement, and means for controlling the movement of said arm, said controlling means being adapted to permit said arm to swing rapidly or slowly.
11. In a device of the type described, a support, a weighted gravity actuated arm pivotally carried by said support, means for locking said arm from movement, a switch member associated with said arm, a second

switch member carried by said support, said switch members being adapted to contact with each other when said arm is held by said locking means and to disengage each other when said locking means has been opened.

12. In a device of the type described, a support, an arm pivotally carried by said support, said arm having a recess therein, 10 a weighted gravity actuated arm pivotally carried by said support, a hook carried by said second named arm and adapted to be received in the recess of said first named arm, means for locking said first named 15 arm from movement, said first named arm having a curved portion adjacent to the recess, said curved portion being adapted to force said hook out of engagement with the recess when said first named arm is released 20 by said locking means.

13. A device of the type described comprising a support, a brake engaging member carried by said support, means carried by said support for releasing said member, 25 means carried by said support for controlling the movement of said member after it has been released, and means also carried by said support for actuating the control means.

30 14. A device of the type described comprising a support, a brake arm movably carried by said support, means carried by said support for controlling the movement of said

arm, means carried by said support for releasing said arm, and means carried by said support for adjusting said control means to determine the speed at which the arm moves. 35

15. The combination with a brake mechanism, of a mine hoist, and a hoisting drum 40 for said hoist, of a support, a gravity operated brake engaging member carried by said support and arranged to connect directly with said brake mechanism, means carried by said support for locking said member against movement, and means carried by 45 said support arranged to cooperate with said hoisting drum with which said brake mechanism is associated for releasing said locking means when said hoisting drum overspeeds or overruns its normal limits of 50 travel.

16. The combination with a hoisting drum and an automatic brake applying means associated therewith arranged to function 55 when said hoisting drum overspeeds or overwinds, of hydraulic means for controlling the movement of said automatic brake applying means to cause the brakes to be applied at a variable rate of speed, and means cooperating with the hoisting drum and associated with the hydraulic means to automatically control the hydraulic means for regulating the brakes depending upon the position of the cage or skip hoisted by said hoisting drum. 60

HENRY H. LOGAN.
